UNITED STATES PATENT OFFICE.

CHANCE, MONTEL HOAG, OF LONG BEACH, CALIFORNIA, ASSIGNOR OF ONE-HALF TO
IRVING B. FUNK, OF ALHAMBRA, CALIFORNIA.

VALVE-ACTUATING MEANS FOR SAMPLING MACHINES.

Application filed March 5, 1923. Serial No. 623,052.

My invention relates to improvements in sampling machines, in particular that kind of machine used for sampling liquids.

The principal object of my invention is to provide an apparatus for abstracting predetermined amounts of liquid from a flowing body of the same, at predetermined periods of time.

Referring to the drawings, in which the same numbers indicate like parts:

Fig. 1 is a view of my apparatus as a whole.

Fig. 2 is a view, in part section, of my apparatus in one operative position.

Fig. 3 is a view of my apparatus in a second operative position.

Fig. 4 is a view of my apparatus in a third operative position.

Fig. 5 is a sectional view of part of the apparatus.

Fig. 6 is a front view of Fig. 5.

1 is a pipe which is attached to a pipe line for gas, oil, water, or other fluids, and is coupled to a casing 2 containing a partition 2' having an orifice 3 therein in which is seated a valve 4 for opening or closing 3. Valve 4 is held in the casing by a gland 5 and valve stem 6 is connected pivotally through 6' to a bar or lever 7.

To one end of 7 is pivoted a connecting rod 8 and to the other end is pivoted a connecting rod 9, 8 and 9 being pivoted respectively on levers 11 and 10.

The whole apparatus is mounted on a base 18, part of which consists of a fulcrum 12 on which 10 and 11 are pivoted through an eccentric 13, which is shown in detail in Fig. 5, and one end of 10 and 11 are flexibly held to 18 by springs 17 and 16 respectively.

It is to be especially noted that one end of 7 is joined to one end of 11 by connecting rod 8, while the other end of 7 is joined by connecting rod 9 to one end of 10 and in this manner it will be noted that one end of 10 and one end of 11 are free to move except as hereinafter described.

One end of both 10 and 11 is designed to rest on the face of a specially designed cam 14, driven by shaft 15 connected to a suitable source of power, which in this present instance consists of a small electric motor 23, whose shaft 22 revolves a slotted crank 21 which actuates 15 and 14 by means of a crank 19 and a crank pin 20, thus giving a suitable motor speed. However, any other suitable

form of prime mover may be used to actuate cam 14.

1' is a pipe coupled to the valve casing 2 and serves to draw off samples of liquid according to the opening and closing of valve 4.

The operation is as follows:

Cam 14 being revolved at a suitable rate of speed, depending on the number of samples per hour required, gradually elevates one end of 10 and 11, as shown in Fig. 2, until these ends reach an abrupt face in the cam; whereupon the end of 10 is designed to first drop off the face of the cam, as shown in Fig. 3.

This action causes, by the pull of spring 17, the actuation of valve 6 through lever 7 and connecting rod 9, because it will be here noted that one end of 11 is still on the high side of the cam face. This action causes valve 4 to drop, whereby 3 is opened a predetermined distance for the passage of a liquid sample therethrough, which sample passes through 1' to a suitable receptacle.

A further revolving of cam 14 now causes one end of 11 to drop to the same position occupied by 10; this action being accelerated by spring 16, and the other end of 11 causes valve 4 to be again seated through the movement of lever 7 and connecting rod 8, as shown in Fig. 4.

Thus it will be seen that the action of the apparatus for opening valve 4 depends on the relative position of pivot 6' and this position is governed by the location of the ends of levers 10' and 11, with respect to each other, on the face of cam 14.

Hence, the particular time for opening valve 4 will be controlled by the speed of cam 14 and the period of time during which 4 remains open will be controlled by the position of the end of 10, on the face of cam 14 with respect to the end of 11.

This is accomplished by the movement of eccentric 13, whereon 10 is mounted eccentrically with respect to 11, as shown in Fig. 5 in which 13 is the eccentric body actuated through a slot 13' and whereon 11 is centrally and pivotally mounted and 10 is eccentrically and pivotally mounted. 10 is held on 13 by a cap-screw 26 and washer 25, while 10, 11, and 13 are firmly held to 12 by a nut 24.

By inserting a screw-driver in 13' and revolving 13 a predetermined distance, the

eccentricity of 13 will cause 10 to be moved towards 8 from 14, thereby permitting the end of 10 resting on the face of cam 14 to drop off the abrupt face of 14 a predetermined distance ahead of the end of 11 whereby valve 4 is opened, as already described, and remains open a greater or less time for the purpose of withdrawing a greater or less sample through 3 and 1'.
10

Therefore, as long as the angular position of the ends of 10 and 11, with respect to the face of cam 14, is the same, it will be seen that there can be no movement at 6', but as soon as this angular position of the 15 two ends is changed, the movement at 6' will occur proportionately to the depth of the abrupt face of cam 14 through the instrumentalities described.

20 My apparatus can be used for drawing off other than fluid samples, such as sand, etc., and while I find the greatest application of my invention in sampling liquids from pipe lines, it is obvious the same may be used on stationary bodies of liquids or in any place 25 where it is desired to withdraw samples of specified volumes at specified times.

I claim:—

30 1. The combination with a conduit of a valve, a pair of pivoted levers operatively connected with the valve, a cam for raising the ends of the levers simultaneously and lowering the ends at different time periods, and a spring for each lever for causing said ends to be lowered quickly.

35 2. The combination with a conduit of a valve, a base, a pair of levers connected to the base by a pivot, connections between said levers and said valve, a cam for raising and lowering the ends of said levers at pre-determined periods and means in said pivot for varying said periods.

40 3. The combination with a conduit of a valve adapted to open and close the conduit and means to actuate the valve, said means comprising a pair of levers connected with the valve, and means adapted to engage both of the levers and to release one of the levers in advance of release of the other for momentary actuation of the valve.

45 50 4. The combination with a conduit of a valve adapted to open and close the conduit

and means to actuate the valve, said means comprising a pair of levers connected with the valve, and means adapted to engage both of the levers and to release one of the levers 55 in advance of release of the other for momentary actuation of the valve, one lever extending beyond the other whereby the one lever is held by said engaging means following the release of said other lever. 60

5. The combination with a conduit of a valve adapted to open and close the conduit and means to actuate the valve, said means including a pair of levers connected with the valve, one of said levers extending beyond 65 the other, and a cam engaging both the said levers and adapted to release the shorter lever in advance of release of the longer lever for actuation of the valve.

6. The combination with a conduit of a 70 valve adapted to open and close the conduit and means to actuate the valve comprising a bar connected intermediate its ends with said valve, a pair of rods connected with the respective ends of the bar, a pair of levers, 75 means for fulcruming said levers, each lever being connected respectively with a rod, means for normally returning the levers to initial position and means for actuating said levers adapted to release one of the levers 80 in advance of release of the other for actuation of the valve.

7. The combination with a conduit of a valve adapted to open and close the conduit and means to actuate the valve comprising 85 a bar connected intermediate its ends with said valve, a pair of rods connected with the respective ends of the bar, a pair of levers, means for fulcruming said levers, each lever being connected respectively with a rod, means for normally returning the levers to initial position, one lever being longer than the other, and a cam 90 for actuating said levers by engagement with the ends thereof whereby the shorter lever is released in advance of release of the other lever for momentary actuation of the valve. 95

Signed at Wilmington, in the county of Los Angeles, and State of California, this 100 28 day of February A. D. 1923.

CHANCE MONTEL HOAG.
